Primary Examiner — Rhea Shields*(74) Attorney, Agent, or Firm* — Renaissance IP Law Group LLP(57) **CLAIM**

The ornamental design for a battery, as shown and described.

DESCRIPTION

Fig. 1.1 is a top, front and right side perspective view of a battery showing my new design;

Fig. 1.2 is a front elevation view thereof;

Fig. 1.3 is a rear elevation view thereof;

Fig. 1.4 is a left side elevation view thereof;

Fig. 1.5 is a right side elevation view thereof;

Fig. 1.6 is a top plan view thereof;

Fig. 1.7 is a bottom plan view thereof; and

Fig. 1.8 is another top, front and right side perspective view thereof wherein the cable is shown pulled out.

The shade lines in the figures show contour and not surface ornamentation.

In the drawings, the broken lines are for the purpose of illustrating environment only and form no part of the claimed design.
